UNITED STATES PATENT OFFICE

LOUIS C. HYATT, OF ALBANY, NEW YORK, ASSIGNOR TO CONSOLIDATED CAR-HEATING COMPANY, INC., OF ALBANY, NEW YORK, A CORPORATION OF NEW YORK

BUS HEATER

Application filed July 15, 1927. Serial No. 205,949.

For a detailed description of the present form of my invention, reference may be had to the following specification and to the accompanying drawings forming a part thereof, wherein

5 Fig. 1 is a side elevation of a bus equipped with my heater;

Fig. 2 is a plan of the heater in position;

10 Fig. 3 is an enlarged plan of the heater alone and

15 Fig. 4 is a longitudinal vertical section of Fig. 3.

My invention relates to heaters for busses or analogous gas-engine propelled vehicles of the type wherein the toxic gases of the engine exhaust are first rendered innocuous by combustion and the heat of the combustion is taken from the innocuous side of the burner and transferred to the body of the bus. It 20 is my present purpose to provide, as a definite separable article, a device based on this principle which may be applied to busses generally.

Referring to the drawing, A represents the 25 usual exhaust pipe of the bus engine. This pipe, as shown in Fig. 1, drops down on the exhaust side of the engine to a level below the body of the bus. Instead, however, of opening into the atmosphere at that point as is customary, I connect it to a pipe A², which, 30 as shown in dotted lines, Figure 2, extends transversely across the engine to the intake side thereof and is connected to my apparatus, indicated as a whole, by the letter B.

35 My apparatus B comprises a long cylinder R located beneath the bus body and extending longitudinally in a line below the seat or seats on one side of the vehicle. The cylinder R is divided into two parts by a transverse partition R³ (see Fig. 4) which defines what I term the toxic line. The part of the heater at the right of this partition may be termed the non-toxic or part-combustion part. The space on the left of this partition, 40 as it appears in Fig. 4, is unsafe and the space on the right thereof safe for driving heat from the interior combustion tube S to heat the bus body. One cast metal section S² of this combustion tube S passes longitudinally through the partition R³ aforesaid.

The section on the right is welded to S² but the section on the left may be merely bolted thereto. The burner apparatus within tube S constitutes the subject matter of my application for Patent No. 189,320, filed May 6, 1927, and is here shown and described only as a means to aid the understanding of the invention which I now disclose herein and claim. At the right of partition R³, on the non-toxic side thereof, a duct R² leads upward from the cylinder R into the body of the vehicle as shown in Fig. 1. The pipe A² aforesaid, which receives the exhaust flow from exhaust pipe A, enters the left hand end of tube S which protrudes through the left hand head of cylinder R, as said tube and cylinder are shown in Fig. 4. Around the end of pipe A² is a conical sleeve 3 spaced away from said pipe. Through said space air is drawn through slots 2, 2 in tube S by the suction of the jet issuing from A². This is the air which, mixing with the jet, not only maintains the combustion but also supplies the oxygen that converts the poisonous monoxide (CO) to the innocuous dioxide (CO₂) of carbon. This air is taken from within casing R as hereinafter explained. At 13 and 15 are Davy screens constructed to offer no material resistance to the passage of the jet from A² but to limit the vibration of the combustion flame which vibration results from the pulsating pressure of the exhaust. The spark plug 14 is constantly in operation to maintain the flame. At the right of the spark plug is the stabilizer which includes a 20 perforated tube G preferably tapered as shown with a perforated cone H and a perforated partition H². The function of the stabilizer and the screens 13 and 15 is to keep the combustion from stopping at unexpected times, a trouble which has long prevented the practical use of exhaust combustion. The tube D is a refractory lining for the section S². A pipe T, shown in Figs. 1 and 2, communicates at one end with a scoop-shaped enlargement W on the under side of cylinder R which opens into said cylinder at the right of the above mentioned partition R³ at the toxic line. It also delivers air into the compartment at the left of said partition 30 35 40 45 50 55 60 65 70 75 80 85 90 95 100

which air is that drawn, as aforesaid, through slots 2, 2 in tube S. By this means any possible leakage of exhaust gas into cylinder R is sucked back into tube S through slots 2, 2, instead of escaping into the atmosphere. At its opposite end pipe T connects with the smaller end of a cone T^2 whose larger end points forward in the direction of progress of the vehicle.

10 The above described apparatus is in the nature of a self-contained attachment which may be applied to buses already built, since it does not involve any modification of the bus structure. Its operation is as follows:

15 Assuming the engine to be in operation the exhaust gases issuing from pipe A² draw in air by injector suction through cone 3, which air is mingled in chamber 12 with the gases and the mixture passes freely through screens 13 and 15 into chamber 16 where it is ignited by plug 14. Heretofore the combustion could not be readily maintained, it being my discovery that this was due to the wide fluctuations of pressure and consequent velocity in 20 the exhaust. These fluctuations are due not only to the succeeding explosions in the engine cylinders but also to a variety of other causes, including the composition of the fuel and the character of individual engines and 25 individual makes of engine and carburetter. Under these fluctuations the origin point of the flame would vibrate back and forth and ultimately would move so far to the exit side as to outstrip the velocity of flame propagation 30 and so become extinguished. In my construction the Davy screens 13 and 15 limit the left-ward excursion of the flame while the stabilizer, without materially obstructing the flow, acts to spread out or disperse it and 35 maintain enough of the gas without the ignition region to prevent its extinction. Thus a certain normal flow enters central tube C and passes through the perforated partition H² and out. But an increased flow will be dispersed or spread out into the space between 40 tube C and the inner wall of tube S and there remain subject to the flame through the orifices in the wall of tube C. This stabilized form of burner is the special subject matter 45 of my aforesaid application No. 189,320. In my present application this burner is contained in a standardized casing R of greater diameter than the burner itself. The air in front of the advancing vehicle is drawn into 50 the cone T^2 and passes through the air duct T into the enlargement W on the under side of casing R and enters the casing on the right-hand side, as viewed in Fig. 4, of the aforesaid partition R² and leaves casing R by the duct R² which leads to the interior 55 of the vehicle body. By this means the incoming air is immediately heated only by the heat in the non-toxic portion of the flow through the interior of the heater. Thereby 60 I utilize what has heretofore been a noxious 65

waste product to heat the vehicle in a safe and innocuous manner. The exhaust gases from the engine are delivered by the pipe A² into the tube S at a temperature of about 400 degrees, but after recombustion reaches a temperature of 1500 to 2000 degrees. This provides an amount of heat adequate for all emergency requirements in the largest bus or analogous gas-engine driven vehicle while the system is free from contamination by the noxious contents of the raw exhaust.

70 What I claim as new and desire to secure by Letters Patent is:

1. A bus heater comprising a casing provided with a transverse partition, a gas burner extending longitudinally of the casing and through said partition, an air intake for the burner located on one side of said partition, said casing on the other side of said partition having an air chamber heated by said burner, means for introducing fresh air into said chamber, and means for conducting heated air from said chamber.

75 2. A heater for vehicles comprising a combustion tube having an inlet at one end and an outlet for products of combustion at the other end, means for introducing exhaust gases from an internal combustion engine into said tube at said inlet end, means for mixing air with said exhaust gases, means for reburning the mixture of exhaust gases and air within said tube at a position near said inlet end, means providing an air chamber surrounding said tube between the outlet end of said tube and the position at which said mixture is reburned, so that air in said chamber will be heated, means for introducing air into said chamber, means for conducting heated air from said chamber, and means for closing said air chamber against admission of exhaust gases thereinto.

80 3. A heater for vehicles comprising a casing, a burner extending longitudinally through said casing, a partition extending transversely across the space between said burner and the adjacent surrounding wall of said casing, means for introducing a mixture of air and exhaust gases to said burner on one side of said partition, means for reburning said mixture, said partition occupying a position approximately coinciding with the location at which the reburning of said mixture takes place, an air chamber located on the other side of said partition and heated by said burner, and means for discharging heated air from said casing.

85 4. A heater for vehicles comprising a casing, a tube extending through said casing and having an inlet end and a discharge end, the space between said tube and said casing including a combustion chamber and an air chamber in longitudinally spaced relation, means for introducing a mixture of exhaust gases and air in the inlet end of said tube, 90 means for reburning said mixture within that 95

- portion of said tube enclosed by said combustion chamber, means for introducing air into said air chamber so as to be heated by the products of combustion flowing through the remaining portion of said tube, means for conducting heated air from said casing, and means segregating the combustion chamber from the air chamber so as to prevent introduction of toxic gases from said combustion chamber to said air chamber.
- 5 10 5. A heater for vehicles comprising a combustion tube having an inlet at one end and an outlet for products of combustion at the other end, means for introducing exhaust gases from an internal combustion engine into said tube at said inlet end, means for mixing air with said exhaust gases, means for reburning the mixture of exhaust gases and air within said tube at a position near said inlet end, 15 means providing an air chamber surrounding said tube between the outlet end of said tube and the position at which said mixture is reburned, so that air in said chamber will be heated, means for introducing air into 20 said chamber, means for conducting heated air from said chamber, means for closing said air chamber against admission of exhaust gases thereinto, and means within said tube for reducing fluctuations of the mixture 25 during the reburning thereof.
- 30 6. A heater for vehicles comprising a casing, a tube extending through said casing and having an inlet end and a discharge end, the space between said tube and said casing including a combustion chamber and an air chamber in longitudinally spaced relation, means for introducing a mixture of exhaust gases and air in the inlet end of said tube, means for reburning said mixture within that 35 portion of said tube enclosed by said combustion chamber, means for introducing air into 40 said air chamber so as to be heated by the products of combustion flowing through the remaining portion of said tube, means for 45 conducting heated air from said casing, means segregating the combustion chamber from the air chamber so as to prevent introduction of toxic gases from said combustion chamber to said air chamber, and means for 50 reducing fluctuations of the mixture during the reburning thereof.

Signed at Albany, county of Albany, State of New York, this 13th day of July, 1927.

LOUIS C. HYATT.
